UNITED STATES PATENT OFFICE.

JESSE BALDWIN, OF DETROIT, MICHIGAN, ASSIGNOR TO B. C. CASE, OF DETROIT, MICHIGAN.

CARBURETER.

1,373,644.

Specification of Letters Patent.

Patented Apr. 5, 1921.

Application filed June 7, 1919. Serial No. 302,478.

To all whom it may concern:

Be it known that I, JESSE BALDWIN, a citizen of the United States of America, residing at Detroit, in the county of Wayne and 5 State of Michigan, have invented certain new and useful Improvements in Carbureters, of which the following is a specification, reference being had therein to the accompanying drawings.

10 This invention relates to carbureters and special reference to that type wherein a valvular air and fuel regulating member is actuated by reduction of atmospheric pressure or suction produced within the carbureter by an internal combustion engine 15 served by the carbureter.

My invention will be hereinafter more fully described and then claimed, and reference will now be had to the drawings, 20 wherein—

Figure 1 is a vertical longitudinal sectional view of the carbureter;

Fig. 2 is a horizontal view showing the relative positions of the carbureter body and 25 float chamber, and

Fig. 3 is a side elevation of the carbureter partly broken away and partly in section.

In the drawing, the reference numeral 1 denotes a cylindrical carbureter body or 30 bowl which has one side thereof provided with an air intake connection 2 devoid of any throttle or butterfly valve. At the opposite side of the carbureter body is a float chamber 3 having a detachable cover 4 and 35 said float chamber is provided with an offset portion 5 of less depth than the chamber to accommodate a float actuated valve 6 movable to and from a fuel intake connection 7 adapted to admit fuel to the chamber 3 40 from a tank or other receptacle (not shown). The valve 6 is carried by the short arm of a float lever 8 pivoted on a transverse pin 9 within the offset portion 5 of the float chamber 3, and the long arm of said float lever 45 has a conventional form of float 10 within the chamber 3.

The bottom of the carbureter body 1 is provided with a depression or basin 11 having a central port or orifice 12 communicating with a tubular body 13, and the lower end of said valve body has a conventional form of stuffing box 14 for the adjustable stem 15 of a needle valve 16, said needle valve being adjustable relative to the port 55 or orifice 12 so that it may be set to regulate

the flow of fuel from the float chamber 3 into the basin 11 of the carbureter body. Communication between the valve body 13 and the float chamber 3 is established by a lateral conduit 17 which also serves to brace the 60 valve 13 relative to the float chamber 3, as best shown in Fig. 1.

The top of the carbureter body 1 is closed by a wall 18 having a central opening 19 and a peripheral seat 20, and mounted on 65 the seat 20 is the lower enlarged end 21 of a manifold connection 22 adapted to be connected to the manifold of the internal combustion engine in the usual and well known manner. The lower enlarged end of the 70 manifold connection 22 affords a chamber 23 above the top wall 18 of the carbureter body and the bore of the manifold connection aligns with the opening 19 of the wall 18.

Slidable in the manifold connection 22 and 75 the opening 19 of the wall 18 is an air and fuel regulating member 24 in the form of a tube that has a peripheral flange 25 extending into the chamber 23 and slidable therein. The lower end of the tubular member 24 is 80 in proximity to the basin 11 and is contracted as at 26, to a diameter approximately that of the basin 11, so that said basin may represent the bottom of the tubular member but be normally separated therefrom by the annular space between the bottom of the carbureter body and the lower end of the tubular member.

In the manifold connection 22 is a throttle or butterfly valve 27 having its operating 90 shaft 28 provided with a crank 29 at one end thereof and operating means 30 at the opposite end thereof, said operating means being of conventional form. The crank 29 is pivotally connected by a link 31 to a rod 32 95 extending into the chamber 23 above the flange 25 therein, and said rod is adapted to limit the upward movement of the member 24 and cause said member to be seated when the throttle 27 is closed. The rod 32 being 100 controlled by the throttle 27 constitutes means for limiting the opening movement of the valvular member 24, and means for closing said valvular member should there be any tendency of said member to remain 105 open.

The manifold connection 22 has an enlargement 33 providing an angular by-path 34 which communicates with the upper end of the chamber 23 and with the manifold 110

connection 22 in a plane below the throttle 27. Adjustable in the enlargement 33 is a small screw needle valve 35 which extends into the by-path 34 to restrict the passage, 5 or communication between the chamber 23 and the manifold connection 22, and after the valve 35 has been adjusted, it may be held by a conventional form of locking device 36 mounted on the enlargement 33.

10 The lower enlarged end 21 of the manifold connection 22 may be connected to the upper end of the carbureter body 1 by any suitable means at such places indicated 37, and with the manifold connection 22 made 15 separate from the carbureter body it is easy to assemble or install the valvular member 24.

When placing the carbureter in use it is only necessary to adjust the valves 16 and 20 35 and the degree of adjustment depends upon the type of internal combustion engine served by the carbureter. Assuming that the adjustments have been made for a proper fuel supply to the engine, and that 25 the throttle 27 is slightly open so that an engine may idle, then the air from the intake connection 2 passing under the lower end of the valvular member 24 lifts sufficient fuel from the basin 11 to serve the engine. 30 As the throttle 27 is opened and the speed of the engine picks up, the partial vacuum or reduction of atmospheric pressure within the chamber 23 elevates the valvular member 24 and permits of a greater quantity of 35 air to pass under said member, over the basin 11, so that a greater quantity of fuel will be carried upwardly through the valvular member to the engine. The partial vacuum in the chamber 23 is attained 40 through the medium of a by-path 34 and the opening movement of the valvular member 24 is regulated by the rod 32. When the throttle 27 is closed the rod 32 is lowered and by engaging the flange 25 of the valvular member 24, said member is lowered to 45 reduce the volume of air passing under said member and over the fuel basin 11 of the carbureter.

The valvular member 24 constitutes a mixing chamber that is constantly in communication with the supply of fuel, as gasoline within the basin 11 and said basin always contains sufficient fuel for starting or engine idling purposes.

It is thought that the operation and 55 utility of my invention will be apparent without further description and while in the drawings there is illustrated a preferred embodiment of my invention, it is to be understood that the structural elements are 60 susceptible to such variations and modifications as fall within the scope of the appended claim.

What I claim is:

A carbureter of the type described comprising a body having an air intake connection and a fuel basin, a throttle in said body, a manifold connection having a lower large end seated on said body, a sleeve-like valvular member slidable in said body and said manifold connection and having a lower contracted end adjacent the bottom of said basin to control the supply of air to said manifold connection, said valvular member coöperating with said manifold connection 75 in providing an annular chamber communicating with the manifold connection above said valvular member and adapted to have a partial vacuum produced therein, a peripheral flange on said valvular member in 80 said annular chamber adapted to raise said valvular member when there is a partial vacuum in said chamber, and a rod extending into said annular chamber and connected to said throttle outside of said body 85 and adapted to engage the flange of said valvular member to lower said valvular member and also limit the forward movement thereof.

In testimony whereof I affix my signature 90 in the presence of two witnesses.

JESSE BALDWIN.
